UNITED STATES PATENT OFFICE

WOLDEMAR HEINITZ, OF CHEMNITZ, GERMANY, ASSIGNOR TO SCHUBERT & SALZER MASCHINENFABRIK, AKTIENGESELLSCHAFT, OF CHEMNITZ, GERMANY

METHOD OF KNITTING HOSIERY ON FLAT KNITTING MACHINES

Application filed October 24, 1928, Serial No. 314,805, and in Germany October 2, 1928.

My invention relates to a method of knitting hosiery on flat knitting machines, and to the hosiery obtained thereby.

According to the new method the work, for instance a stocking, is started at the welt, narrowed by the old method at the calf and then widened at either side at the beginning of the heel, but the border loops are only set on alternately, whereupon several rows are knitted plain and thereafter only the lower side of the heel is narrowed, without successive narrowing of the instep.

With the new method not only much more suitable goods, such as stockings, are obtained, but the manufacture of such goods is also greatly expedited.

A stocking obtained by the new method is more suitable than the usual stocking, as it lacks the characteristic narrowing row of loops in the upper portion of the heel which shows distinctly with low shoes. Furthermore the stocking does not require any narrowing and therefore is more durable, and by the simultaneous widening of the path of the thread guide proper loops are obtained at the edges.

The manufacture is expedited because with the setting on of loops it is not necessary to arrest the machine or to reduce its speed as in narrowing, and because after some plain rows have been knitted, the narrowing of the lower portion of the heel without subsequent narrowing at the instep imparts to the heel a more correct shape.

In the drawings affixed to this specification and forming part thereof the heel part of a stocking made according to my invention and several stages of its manufacture are illustrated diagrammatically by way of example.

In the drawings:

Fig. 1 is an elevation of the spread out heel part of a stocking made in accordance with this invention,

Fig. 2 is a diagram of loops illustrating the setting on and the alternate formation of the loops at the edges,

Fig. 3 shows the part illustrated in Fig. 1 sewn to a complete heel.

Referring to the drawings, after the stocking has been finished and narrowed at the

leg, the edges from $a-a'$ to $b-b'$ are not covered, as usual but the widening is obtained merely by setting on loops, and proper loops are formed along the edges by the simultaneous widening of the thread-guide path. A plurality of plain rows are then knitted from $b-b'$ to $c-c'$ and the fabric is narrowed from $c-c'$ to $d-d'$ in order to form the lower part of the heel. Narrowing at the instep is entirely dispensed with. After the lower part of the heel has been completed the heel is finished as usual.

Fig. 2 illustrates the edges from a to c and a' to c' on a larger scale, showing the formation of the loops at the edges.

In the finished heel (Fig. 3) the parts of the fabric illustrated in Fig. 1 are indicated by corresponding reference letters.

In manufacturing hosiery in accordance with my improved method, the stocking, as stated hereinbefore, is begun in the customary way at the welt. With the beginning of the heel at its upper part, the thread guide path is widened by two needles for every course of loops, while one loop is struck. Following this, a few straight courses are worked, and then the lower part of the heel is narrowed without a subsequent wedge-like covering.

It is to be noted with reference to the drawings, particularly Figure 2 thereof, that after finishing the leg portion of the stocking as far as $a-a'$, that is, course II, and the fabric has been worked to the series of loops f , with the thread guided in the direction indicated by the arrow, the thread guide path in course III is widened, so that the thread is shifted on the needles of the series g . Before reversing the thread guide path, another loop is struck upon the needle of series h , so that in the course IV, two needles are covered by the thread. The thread which at first assumes the position indicated by the broken lines, is subsequently drawn to the position shown by the full lines, since the loops are not supported by the formation of the loops in the preceding row. The process is repeated at the opposite side of course IV, and so on continually alternating. Therefore,

it will be evident that true marginal loops

are formed, which in the finished product, result in a better fitting of the foot and eliminate the usual widening marks.

Various changes may be made in the ⁵ tails disclosed in the foregoing specification without departing from the invention or sacrificing the advantages thereof.

In the claims affixed to this specification no selection of any particular modification ¹⁰ of the invention is intended to the exclusion of other modifications thereof and the right to subsequently make claim to any modification not covered by these claims is expressly reserved.

¹⁵ I claim:—

1. The herein described method of manufacturing hosiery in one operation upon flat knitting machines, comprising beginning the goods at the welt, widening the upper part ²⁰ of the heel portion by increasing the successive courses alternately by two needles for each course while one loop is struck, knitting several straight courses, and then narrowing the lower part of the heel portion without ²⁵ subsequent wedge-like covering.

2. As a new article of manufacture, a stocking having loops alternately set on in each successive course forming the upper part of the heel portion whereby to eliminate widening marks, several courses in the intermediate part of the heel portion being knitted straight, and the courses forming the lower part of the heel portion being narrowed without subsequent ³⁰ wedge-like covering.

³⁵ In testimony whereof I affix my signature.
WOLDEMAR HEINITZ.
